UNITED STATES PATENT OFFICE.

DOROTHY LONG, OF NEW YORK, N. Y., ASSIGNOR TO FRANKLIN SIMON & COMPANY, INC., OF NEW YORK, N. Y., A CORPORATION OF NEW YORK.

DESIGN FOR A TURBAN.

Application filed March 12, 1929. Serial No. 30,433. Term of patent 3½ years.

To all whom it may concern:

Be it known that I, DOROTHY LONG, a citizen of the United States, and a resident of the city of New York, borough of Manhattan, in the county of New York and State of New York, have invented the new, original, and ornamental Design for Turban, of which the following is a specification.

Reference is had to the accompanying drawing, forming part thereof, wherein

I claim:

The ornamental design for a turban substantially as shown and described.

Signed at New York, in the county of New York and State of New York this 8th day of March A. D. 1929.

DOROTHY LONG.
